UNITED STATES PATENT OFFICE.

FREDERICK C. BAUER, OF PHILADELPHIA, PENNSYLVANIA.

TOY GRAVITY-RAILWAY.

1,368,781.

Specification of Letters Patent. Patented Feb. 15, 1921.

Application filed October 12, 1920. Serial No. 416,443.

To all whom it may concern:

Be it known that I, FREDERICK C. BAUER, a citizen of the United States, residing in the city and county of Philadelphia, State 5 of Pennsylvania, have invented a new and useful Toy Gravity-Railway, of which the following is a specification.

My invention relates to a toy gravity railway and consists of upper and lower platforms, and a supporting structure therefor, said platforms being inclined in opposite directions whereby a toy car placed on the upper platform may be directed automatically 10 therefrom to said railways as its start, and after descending the latter will be directed automatically on the lower platform as its return, means being also provided for coupling said platforms with the adjacent terminals of the railways, and other details 15 20 are provided as will be hereinafter set forth.

The invention is satisfactorily illustrated in the accompanying drawing, but the important instrumentalities thereof may be varied, and so it is to be understood that the invention 25 is not limited to the specific details shown and described, as long as they are within the spirit or scope of the claims.

Figure 1 represents a perspective view of a toy gravity railway embodying my invention.

Fig. 2 represents a perspective view of the upper platform of the device.

Fig. 3 represents a perspective view of the lower platform of the device.

Similar numerals of reference indicate 30 corresponding parts in the figures.

Referring to the drawings,

1 designates a main frame consisting of the columns 2, the base 3 on which said 40 frame is placed and supported and the strengthening braces 4 attached to the adjacent columns.

Connected removably with the upper ends of the columns 2 are columns 5 with 45 strengthening braces 6 therefor to form a supplemental top frame with a roof thereon.

Between the columns 5 and supported on the braces 6 is the platform 7 which is inclined downward to the left and on whose 50 left hand end are the sections of railroad rails 8 tubular in form.

Connected with the base 3 between the columns 2 is the platform 9 which is inclined to the right and on whose left hand 55 end are the sections of railroad rails 10 tubular in form. On the columns 2 are fitted

the side roofs 11 which are supported on the braces 6 and so held in position.

The platforms 7 and 9 consist each of a floor 12, and guard walls 13 on the sides 60 thereof, said walls being adapted to prevent the car when occupying either platform from falling laterally therefrom.

The lower platform 9 has thereon at the right hand end thereof the cross bar 14 65 which is so located as to form a stop for the car when it runs on said platform to prevent it from leaving the latter at said end. The side guards are turned up from the floor forming tubular members which stiffen the 70 same, and the cross bar 13 is connected with the guard of the lower platform adapted to prevent said guards from spreading, it being desirable to make the platforms of light but durable material so that provision is 75 made to strengthen the same on their sides, whereby they are enabled to endure the rough usage to which they are subjected by children in assembling the toy, while playing with the same, and disassembling and 80 folding its parts.

The upper frames and the main frame may be disconnected and they with the platforms and their appurtenances and the base may be folded and packed together forming 85 a bundle convenient for storage and transportation.

15 designates a spiral railway which is supported on the shoes 16 and columns 17. The terminals of the convolutions of said 90 railway are adapted to be coupled with the platforms by the tongues 18 which are adapted to enter the tubular rails 8 and 10 respectively and sockets 19 in the respective terminals of the rails of the railway, said 95 tongues being removable when so desired for uncoupling purposes.

The operation is as follows:—

When the parts are assembled as in Fig. 1, a car is placed on the floor of the upper 100 platform when it will run down thereon by gravity to the beginning of the track of the railway guided thereto by the rails 7, and then run on said track by gravity to the terminal thereof and directed by the rails 105 10 to the floor of the lower platform on which it will be stopped by the cross bar 14.

The operations may be repeated as desired.

The tongues 18 may be withdrawn from 110 the rails 8 and 10 thus disconnecting the railway 1 from the platforms 7 and 9 or

vice versa, and the parts of the toy may be dismantled and folded and packed as has been stated.

Having thus described my invention what 5 I claim as new and desire to secure by Letters Patent, is:—

1. In a toy railway, a frame composed of a base, columns rising therefrom, an upper supporting device on said columns, and platforms 10 inclined in reverse directions supported on said base and device and composed of rail supporting floors, and guards on the sides thereof, said guards rising from said floors.
- 15 2. In a toy railway, a frame composed of a base, columns rising therefrom, an upper supporting device on said columns, and platforms inclined in reverse directions supported on said base and device and composed of

rail supporting floors, guards on the sides 20 thereof, said guards rising from said floors, and a bracing and stop bar on the lower platform connected with the side guards thereof.

3. In a toy railway, a base, columns rising 25 therefrom, an upper supporting member and platforms inclined in reverse direction respectively on said base and upper supporting member, said columns being detachable from said base, and said upper supporting member being detachable from said columns, admitting of the several members being de-mounted and packed together.

FREDERICK C. BAUER.
